UNITED STATES PATENT OFFICE.

JACK L. THOMAS, OF WEWOKA, OKLAHOMA.

VALVE-UNIT ATTACHMENT FOR A SECTIONAL ROTARY PIPE OF A WELL-DRILLING APPARATUS.

Application filed September 6, 1927. Serial No. 217,784.

The present invention relates to improvements in rotary sectional pipes such as are employed in connection with a well drilling apparatus and has reference more particularly to a valve unit attachment for such sectional rotary pipes.

One of the important objects of the present invention is to provide a means for preventing the flow of the mud laden fluid upwardly through the rotary pipe when the pipe has been lowered into the well, said means being moved to an open position by the action of the circulating fluid which is forced downwardly through the rotary pipe by pressure whereby to allow the free passage of the upwardly flowing mud-laden fluid after the pipe has reached the bottom of the well.

A further object of the invention is to provide a valve unit which will at all times be positive and efficient in its operation, the same being further of such construction as to permit the ready installation of the unit between the adjacent ends of one pair of pipe sections comprising the rotary pipe.

A still further object is to provide a valve unit attachment of the above mentioned character which is simple in construction, inexpensive, strong and durable and further well adapted to the purpose for which it is designed.

Other objects and advantages will become apparent during the course of the following description.

In the accompanying drawing forming a part of this application, and in which like numerals indicate like parts throughout the same:

Figure 1 is a vertical sectional view through the valve unit attachment embodying my invention showing the same associated with the adjacent ends of a pair of pipe sections, and

Figure 2 is a sectional view taken substantially on the line 2—2 of Figure 1 looking in a downward direction.

In the drawing wherein for the purpose of illustration is shown the preferred embodiment of my invention, the numeral 1 designates the tubular body portion of the unit, the same being in the form of a pipe

and which pipe is substantially of the same inner and outer diameters as the adjacent sections 2 and 3 of the rotary pipe between which sections the tubular body is to be disposed.

The lower end of the tubular body is formed with the tapered externally threaded neck 4 which is threaded into the similar shaped internally threaded socket 5 provided in the upper end of the lower pipe section 2.

The upper end of this tubular body 1 is formed with a downwardly tapered threaded socket 6 for receiving the externally threaded tapered neck portion 7 formed on the lower end of the upper pipe section, as is clearly illustrated in Figure 1 of the drawing. The lower end of the neck 7 of the upper pipe section 3 does not extend to the bottom of the socket 6 and detachably supported within the space provided between the lower end of the neck 7 and the bottom of the socket 6 is the threaded plug 8, the same being formed with a central bore 9 and as is clearly shown in the drawing the outer peripheral face of this plug is tapered to conform to the tapered socket 6.

The bottom face of the plug 8 around the bore 9 forms a valve seat with which cooperates the conical shaped valve 10 in the manner shown in the full lines in Figure 1 for closing the bore 9 and preventing communication between the tubular body 1 and the upper section 3 of the rotary pipe.

This valve is secured on the upper end of the elongated stem 11 which is slidable through the guide boss 12 formed on the intermediate portion of the member 13 and this member is formed with a pair of diametrically opposed laterally projecting arms 14. A rod 15 is pivotally secured at its lower end to the outer end of each of the laterally extending arms 14 and the upper ends of these rods are threaded for engagement within suitable threaded recesses formed therefor at a pair of diametrically opposed points in the bottom of the plug 8, as also very clearly disclosed in Figure 1. These vertical rods 15 provide a means for supporting the guide boss through which the valve stem 11 is slidable.

The upper face of the plug 8 is formed with suitable recesses shown at 16 to accommodate a spanner wrench whereby said plug may be inserted or removed with respect to the tubular body socket 6.

A pin 17 extends transversely through a suitable eye provided therefor in the lower end of the valve stem 11 and carried by this pin are the complementary semi-circular sections 18 and 19, respectively, which sections form a valve stem actuating disc in the manner to be presently described. The adjacent edges of these sections are formed with interfitting looped portions through which the pin 17 extends thus forming a hinged connection between the complementary sections 18 and 19 and for the purpose of preventing the movement of the sections to a closed position there is formed on one of the sections a depending angularly disposed pin 20 and the manner in which this pin functions is clearly disclosed in the dotted lines in Figure 1.

The operation of my improved valve unit attachment may be briefly described as follows. In lowering the rotary pipe carrying my attachment downwardly into a well, the valve stem 11 is in its lowermost position so that the valve 10 is out of engagement with the plug 8 and the same rests on the guide boss 12, while the complementary sections 18 and 19 of the valve actuating disc are disposed in a substantially vertical position, the pin 20 preventing the sections from coming in contact with each other, and furthermore causing the sections to be slightly disposed in an open position whereby the same can be readily subjected to the mud laden fluid.

As soon as the rotary pipe strikes the mud laden fluid, said fluid will exert an equal pressure on the complementary sections of the valve actuating disc, thereby forcing the sections to a horizontal position, it being understood of course that any appropriate means may be provided for limiting the upward swinging movement of the sections, and when said sections 18 and 19 are in a fully opened position, the force of the mud laden fluid will act directly upon the disc, thereby raising the valve stem 11 and the valve 10 carried on the upper end thereof so that the valve will seat against the plug 8 and thereby cut off communication between the tubular body 1 and the upper pipe section 3 so that the mud circulating fluid can not pass upwardly through the rotary pipe.

After the rotary pipe has reached the bottom of the well, and a circulating fluid is forced downwardly through the pipe, the pressure of said fluid will act against the valve 10 to move the same downwardly to an open position as indicated in dotted lines in Figure 1 so that said fluid will enter the

lower portion of the rotary pipe and permit the free passage of the mud laden fluid upwardly through the pipe.

The simplicity of my improved valve unit enables the same to be readily and easily installed in a rotary pipe of a well drilling apparatus without necessitating any material alterations of the parts of the rotary pipe with which the unit is to be associated, and furthermore said valve mechanism will at all times be positive and efficient in its operation.

While I have shown the preferred embodiment of my invention, it is to be understood that various changes in the size, shape and arrangement of parts may be resorted to without departing from the spirit of the invention and the scope of the appended claims.

Having thus described the invention, what I claim as new and desire to secure by Letters Patent is:—

1. In a valve unit attachment for a sectional rotary pipe of a drilling apparatus, a tubular body adapted for disposition between the adjacent ends of a pair of sections of said rotary pipe, a valve seat supported in the upper portion of the tubular body and affording communication between the tubular body and the upper pipe section, a valve stem slidable vertically in the tubular body, guide means therefor, a valve on the upper end of the stem for cooperation with said valve seat to cut off communication between the tubular body and the upper pipe section, means carried by the lower end of the valve stem for moving the normally lowered valve stem to a raised position to bring the valve into engagement with the seat when said means comes in contact with the mud laden fluid passing upwardly into the tubular body, said last mentioned means comprising a pair of complementary disc forming sections hingedly connected together and carried by the lower end of the valve stem. 100

2. In a valve unit attachment for a sectional rotary pipe of a drilling apparatus, a tubular body adapted for disposition between the adjacent ends of a pair of sections of said rotary pipe, a valve seat supported in the upper portion of the tubular body and affording communication between the tubular body and the upper pipe section, a valve stem slidable vertically in the tubular body, guide means therefor, a valve on the upper end of the stem for cooperation with said valve seat to cut off communication between the tubular body and the upper pipe section, means carried by the lower end of the valve stem for moving the normally lowered valve stem to a raised position to bring the valve into engagement with the seat when said means comes in contact with the mud laden fluid passing upwardly into the tubular body, said last mentioned means comprising 115

a pair of complementary disc forming sections hingedly connected together and carried by the lower end of the valve stem, and means for limiting the inward swinging movement of the sections with respect to each other whereby to maintain said sections in operative position.

3. In a valve unit attachment for a sectional rotary pipe of a drilling apparatus, a tubular body adapted for disposition between the adjacent ends of a pair of sections of said rotary pipe, a valve seat supported in the upper portion of the tubular body and affording communication between the tubular body and the upper pipe section, rods secured at their upper ends to the bottom of the valve seat and extending downwardly into the tubular body, a cross member carried by the lower ends of the rods, a valve stem slideable vertically through the central portion of the cross member, a valve on the upper end of the stem for cooperation with the valve seat to cut off communication between the tubular body and the upper pipe section, and means carried by the lower end of the valve stem for moving the normally lowered valve stem to a raised position to bring the valves into engagement with the seat when said means comes in contact with the mud-laden fluid passing upwardly into the tubular body.

4. In a valve unit attachment for a sectional rotary pipe of a drilling apparatus, a tubular body adapted for disposition between the adjacent ends of a pair of sections of said rotary pipe, a valve seat supported in the upper portion of the tubular body and affording communication between the tubular body and the upper pipe section, rods secured at their upper ends to the bottom of the valve seat and extending downwardly into the tubular body, a cross member carried by the lower ends of the rods, a valve stem slideable vertically through the central portion of the cross member, a valve on the upper end of the stem for cooperation with the valve seat to cut off communication between the tubular body and the upper pipe section, and a pair of complementary disc forming sections hingedly connected together and carried by the lower end of the valve stem and normally disposed in an inoperative position, said sections adapted to be moved to a horizontal position when in contact with the mud-laden fluid passing upwardly into the tubular body, the valve stem being raised to bring the valve into engagement with the seat when the sections are in a horizontal position and in contact with said fluid.

In testimony whereof I affix my signature.
JACK L. THOMAS.
